UNITED STATES PATENT OFFICE.

JOHN S. TIMMONS, OF NEW YORK, N. Y., ASSIGNOR, BY MESNE ASSIGNMENTS, TO
INTERNATIONAL CALLOPHONE CORPORATION, A CORPORATION OF DELA-
WARE.

CASING FOR TELEPHONE SETS.

1,412,982.

Specification of Letters Patent. Patented Apr. 18, 1922.

Application filed May 3, 1919. Serial No. 294,441.

To all whom it may concern:

Be it known that I, JOHN S. TIMMONS, a citizen of the United States, and a resident of New York city, county and State of New York, have invented certain new and useful Improvements in Casings for Telephone Sets, set forth in the following specification.

This invention relates to telephone sets, particularly of the type in which the various operating parts of the set are enclosed in a water-tight casing. A structure of this type very commonly must be exposed to the elements, as it is many times employed on ship-board in an exposed position. A casing suitable to withstand the action of the elements and sea-water is of considerable expense. It is an object of this invention to minimize the expense of such casings by making possible the employment of a standard size and type of casing for all of a various number of circuits and switches. In this type of telephone, selective calling of any one of various stations is an incident and requires the installation upon each set of a number of switches, the number varying according to the number of stations under the control of each individual instrument. In furthering the general object of the invention the relative location of the transmitter and the receiver and their mounting on the casing is such as to aid the inventive object of minimizing the size of the casing required and the facility of examination of the operating parts. It is further an objective feature in the positioning of the transmitter and receiver to provide, in a casing of minimum size to accommodate all the apparatus to be enclosed, a maximum sized window opening to be covered by any one of a number of interchangeable switch-carrying panels, the size of the panel accommodated being such as to mount the maximum number of switches desired for a set of this type and also to mount the minimum number of switches and to provide a ready means in which a set, built up with any one of a various number of controlling switches, may be constructed at minimum expense.

A further object of this invention is to improve the manner in which a casing accommodating a transmitter and a receiver, which operatively open outwardly, may be hermetically enclosed, and their outwardly opening interiors self drained, while, at the same time, the various parts of the apparatus

are made readily accessible by the outwardly swinging door.

Further objects of this invention are to improve in general the enclosing and mounting casing of a telephone set of this general type and will be better understood by reference to the illustrative embodiment of the invention described in the following specification which has reference to the accompanying drawings which form a part hereof, in which like characters designate corresponding parts in the several figures and in which

Fig. 1 is a staggered longitudinal central section through the complete set, with parts broken away, and with the panel elevated; 70

Fig. 2 is a front or face view of the set with the panel removed;

Fig. 3 is a similar view of a panel carrying three switches; and

Fig. 4 is a detail of the manner in which a panel is secured in position.

The casing proper A comprises preferably an elongated, substantially rectangular, box-like casing, preferably of bronze, the base 1 of which is formed integrally with mounting lugs 2 and the ends 3 and 4 of which are preferably rounded off into semi-cylindrical form. The end 4 is provided with a threaded conduit opening 5 leading through an enlargement 6 in the wall 4. Hinged to the casing A in a suitable manner as by hinges 7 is a cover portion 8 having a right-angular flange 9 adapted to seat upon the resilient gasket 10, suitably formed from rubber or any suitable sealing material and mounted in a continuous trough 11 in the face rim of the casing A. Lugs 12 are preferably formed both on the cover 8 and the rim 13 of the casing A to cooperate with threaded clamping bolts 14, serving to force the rim 9 of the cover 8 against the gasket 10 to complete a seal between the cover 8 and the casing A. 90

A transmitter casing B is mounted within the casing A beneath a circular opening 20 in the cover 8 and is removably sealed 100 against the cover 8 by a gasket 21 against which the casing B is forcibly drawn by a mouth-piece and cover 22 having perforations *a* and a flange 23 gripping the outer face of the cover 8 and a threaded inner extension 24 leading into the casing B. The diaphragm *b* has a packing gasket *c* clamped against the shoulder *d* by the threaded jam ring *e* whereby the interior of the case B is hermetically sealed. The space *f* beyond 110

the diaphragm *b* is self draining through the perforations *a* in the protective cover 22. Electrical connections to the transmitter within the casing B are provided through 5 the casing by means of the usual insulated binding posts 25 adapted to cooperate with lead wires 26, which are suitably anchored to the under side of the cover 8, and extend along the cover to the receiver C and downwardly to a terminal board D. The terminal board D is mounted suitably upon and preferably spaced above the base 1 of the casing A as by spacers 27 and screws 28. This board D is serviceable in carrying a 10 number of terminal clips such as the two series 30 and 31, and serves to mount any of the usual apparatus in telephone sets such as may be enclosed within the hood 32, as for example an induction coil or a lightning 15 arrester.

Sufficient space beneath the transmitter casing B and the base 1 of the casing A is left to accommodate any circuit connections which may enter the casing through a conduit threaded into the opening 5. The wires of such connections may pass in the rear of the transmitter casing B into position to be connected with the terminal clips 30 or 30 and 31, as may be desired.

Longitudinally spaced from the transmitter casing B is a receiver casing or horn E which is preferably formed, at least in part, integrally with the cover 8. In the structure shown a mouth covering 40 having perforations *g* covers the opening of the horn E and may be secured in place in any suitable manner. The space *h* within shell E is self draining through the perforations *g*, the outer row of perforations providing drainage openings at the lowest point of the cavity *h* when the casing is mounted for operation vertically on a wall. In the embodiment illustrated the bolt 60, preferably formed integrally with or at least secured 40 to the mouth covering 40, extends through the horn E and serves to draw the cover 40 into position through the medium of a nut 61, the opening for said bolt being sealed by the nut 61 with the aid of a packing washer 50 62, if desired. The receiver structure C, described in detail in my copending application for a telephone receiver, Serial No. 245,386, filed July 17, 1918, enters the side of the horn E, its nipple 63 having screw 55 threaded engagement therewith, which is likewise a hermetically closed connection. Between the receiver C, which cooperates with the horn E, and the cover 8 may be mounted the condenser 41, these parts (the 60 condenser 41 and the receiver C) being well accommodated in the semi-circular end 3 of the casing A. It should be noted particularly how the panel-board D and its associated parts are located in the casing space 65 between the casings B and E rather than

under them, thereby minimizing the depth between cover and base of the casing.

In the cover between the transmitter and receiver openings 220 and 400 is provided a window F, preferably of a width equalling 70 the total width of the casing and in its other dimension approximating the distance between the transmitter and receiver openings 220 and 400.

The parts of the structure so far described 75 may be standard and unvarying, regardless of the number of stations that a finished set is to control. In order cheaply to provide for a varying number of control switches, a panel G is provided having an outwardly 80 projecting marginal bead 44 offset from the plane of the panel and preferably having screw tapped lugs 45 integral therewith to accommodate machine screws 46 projecting outwardly through suitable perforations in 85 the cover 8, it being understood that, in addition to its attachment by the machine screws 46, the panel may be soldered or brazed to the cover, as indicated by the solder 47 in Fig. 4, which shows the details of the panel mounting. This panel may carry one or more up to a predetermined 90 number of switches 48, projecting inwardly through the panel. In the drawings three switches are shown, the inwardly projecting 95 parts being indicated collectively by the numeral 49, but the structure of which for the most part is obscured by the unbroken wall portion 50 of the side of the cover and casing, because the details of these switches 100 are not intended to be a part of this invention. It should, however, be noted that the switches of necessity have inwardly projecting parts which must have space within the casing A for their accommodation between 105 the transmitter casing B and the receiver casing E. 51 is a number or indication strip which may be mounted on the panel G in any suitable manner, as by screws 52, to accommodate any suitable legend, for example, the stations controlled by the apparatus.

What is claimed and what is desired to be secured by United States Letters Patent is:

1. A telephone set comprising a substantially rectangular casing closed on five sides; an openable and closable cover for the sixth side of said casing; a receiver and a transmitter respectively fixed to and carried by said cover at opposite ends thereof and operatively opening outwardly therefrom and leaving a space of a length approximately at least half the width of said casing therebetween; a terminal board mounted within said casing in the space between said transmitter and receiver; said cover having a window between said transmitter and receiver; and a switch carrying panel of the same size as said window for covering said window, whereby various numbers of switches on a 120 125 130

panel may be mounted as a unit in said window in position to cooperate with said terminal board so that said casing may accommodate various numbers of circuits without 5 material alteration of the structure.

2. A telephone set comprising a substantially rectangular casing closed on five sides; an openable and closable cover for the sixth side of said casing; a receiver and a transmitter respectively fixed to and carried by said cover at opposite ends thereof and operatively opening outwardly therefrom and leaving a space of a length approximately at least half the width of said casing therebetween; a terminal board mounted within said casing between said transmitter and receiver; said cover having a window between said transmitter and receiver; and a switch carrying panel of the same size as said window to fit said window and having parts projecting into said casing between said transmitter and receiver which are arranged transversely to said cover whereby a standard panel carrying various numbers of inwardly projecting parts may be associated with said cover without alteration of said casing or cover.

3. In water-proofed telephone apparatus, a box-like casing having an openable and closable cover provided with a transmitter opening and a receiver opening and a water-tight seat between said casing and cover; a transmitter-casing removably carried by said cover and adapted to form a water-tight seal about said transmitter-opening; and a

receiver-horn structure covering said receiver opening and comprising an outwardly opening inwardly closed shell of truncated conical shape making a water-tight closure with said cover.

4. In water-proofed telephone apparatus, a box-like casing having an openable and closable cover provided with a transmitter opening and a receiver opening and a water-tight seat between said casing and cover; 45 a transmitter-casing removably carried by said cover and adapted to form a water-tight seal about said transmitter-opening; a receiver-horn structure covering said receiver opening and comprising an outwardly 50 opening inwardly closed shell of truncated conical shape making a water-tight closure with said cover and having a protective covering for said opening with a bolt passing inwardly through the bottom of said shell 55 to clamp the structure in place.

5. A telephone casing for exposed service having a hinged cover provided with an integral inwardly projecting shell of substantially truncated conical shape to form part 60 of a receiver-horn and extending inwardly for substantially the full depth of said casing; in combination with a receiver mounted on the side of the smaller end of said truncated shell.

In witness whereof I have signed my name to this specification, this 28th day of March, 1919.

JOHN S. TIMMONS.
